UNITED STATES PATENT OFFICE.

THEODORE M. REIMERS, OF OAK PARK, ILLINOIS, ASSIGNOR TO SMITH, BARNES & STROHBER CO., OF CHICAGO, ILLINOIS, A CORPORATION OF ILLINOIS.

TRACKER-BAR MECHANISM.

Application filed May 16, 1922. Serial No. 561,455.

To all whom it may concern:

Be it known that I, THEODORE M. REIMERS, a subject of the King of Denmark, and a resident of Oak Park, in the county of Cook and State of Illinois, have invented certain new and useful Improvements in Tracker-Bar Mechanism; and I do hereby declare that the following is a full, clear, and exact description thereof, reference being had to the accompanying drawings, and to the letters of reference marked thereon, which form a part of this specification.

This invention relates to improvements in tracker bar mechanisms for musical instruments and consists of the matters hereinafter described and more particularly pointed out in the appended claims.

The primary object of the invention is to provide a simple and efficient mechanism for maintaining full registry between the perforations of the music sheet and the openings in the tracker bar.

A further object of the invention is to furnish a mechanism of the kind, which is of simple and economical construction, with comparatively few parts capable of production at small cost and which is so arranged and correlated with the music sheet mechanism, that it may be readily installed in old player pianos or may be embodied in new pianos, without material changes in the construction of said pianos.

A still further object of the invention is to provide a mechanism which is extremely sensitive and quick in its operation so that positive registry is maintained at all times. The aforesaid objects and advantages of the invention will more fully appear as I proceed with my specification.

40 In the drawings:—

Figure 1 is a view in front elevation of a tracker box mechanism of a player piano, embodying my invention;

45 Figure 2 is a vertical section through the same on the line 2—2 of Fig. 1;

Figure 3 is a vertical detail sectional view on an enlarged scale, taken on the line 3—3 of Fig. 1;

50 Figure 4 is a horizontal detail sectional view taken on the line 4—4 of Fig. 3;

Figure 5 is an enlarged view of several of the parts shown at the right hand end of Fig. 1, with some of said parts in a changed relation;

Figures 6 and 7 are vertical detail sectional views taken on the lines 6—6 and 7—7 respectively of Fig. 5;

Figure 8 is a vertical detail sectional view on a further enlarged scale, as taken on the line 8—8 of Fig. 7;

Figure 9 is a perspective view of one of the bracket plates in which the ends of the tracker bar are supported.

Referring now in detail to that embodiment of the invention illustrated in the accompanying drawings as applied to the familiar player piano:—10 indicates the open front tracker box or casing of the player piano. Said box includes the spaced upright side walls 11 and 12 respectively, a top wall 13 and a bottom wall or board 14 which is extended beyond the side wall 12 for the support of the operating gearing and motor.

15 indicates the perforated music sheet wound on a spool 15^a, which is removably connected to horizontal shaft parts 16 and 17 journalled in suitable bearings provided therefor in and near the top ends of the side walls 11 and 12 of the tracker box. The shaft part 17 extends beyond the side wall 12 where it has bearing in an upright standard 18, which is one support for the unwinding and rewinding gear train. 19 indicates the spool upon which the perforated music sheet is wound in the playing operation. Said roll is mounted on horizontal shaft parts 20 and 21 respectively journalled in suitable bearings in and near the bottom ends of the side walls 11 and 12 of the tracker box in the usual manner. The shaft part 21, like the shaft part 17, extends beyond the side wall 12, where it has bearing in the standard 18.

22 indicates the tracker bar. This tracker bar is a channel bar with a convexly rounded front wall 23 and top and bottom horizontal flanges 24—25. The front wall has the usual row of openings 26 with which are connected the nipples 27 (see Fig. 2), one nipple for each opening 26. To said nipples are connected the flexible tubes 28 which in turn are connected to the rigid tubes 28^a secured to the back wall of the casing 10. The ends of the tracker bar 22 are supported in bracket plates 29 (see Figs. 1 and 9) secured to the front edges of the upright end walls 11 and 12 of the box,—the said

end walls being cut away or notched in line with the tracker bar so that the front wall of the tracker bar is flush with the front edges of said upright end walls. Each bracket plate has a front flange 30 which is screwed to the front edges of the associated side wall and a side flange 31 which engages with the inner surface of said side wall. In each side flange is provided a centrally disposed opening 32 in which the ends of the tracker bar have bearing.

34 indicates a horizontal rod located closely above the tracker bar 22. This rod is non-rotative but movable lengthwise and carries opposed guide plates 35, which engage the edges of the music sheet 15. The rod extends through and has sliding bearing support in holes 33 in the bracket plates 29 (see Figure 9). Each guide, as shown, is a vertically elongated plate, with a sleeve 36 at its bottom end engaged upon the rod 34. A part of the metal forming the sleeve is cut and bent back between its ends to form a stop lip 36^a (see Fig. 3). A radial pin 37 fixed to the rod 34 in the opening left in the sleeve by the lip 36^a is engaged by a leaf spring 38 attached to the rear face of the guide plate. Said spring normally urges the guide plate outwardly to hold the perforated music sheet 15 substantially taut, the outward swing of the plate being limited by the engagement of the stop lip 36^a against the stud 37, and the pin by engagement through the hole in the sleeve acting to lock the plate 35 against movement lengthwise of the rod. Each guide plate has a flange 39 formed to define a groove 40 to receive the edge of the music sheet and to hold it from accidental disengagement with the guide plate. As the sheet weaves or shifts laterally, a corresponding movement is imparted to the guide plates 35 and a resultant endwise movement to the rod 34. The right hand end 34^a of said rod extends beyond the right hand wall 12 for a purpose which will appear later. Secured to the rod 34, near the flanges 31 of the bracket 30, are small collars 34^b which limit the endwise movement of said rod.

50 The shafts 17 and 21 of the spools 19 and 15^a are driven in their respective directions in the usual way, as follows: 41 indicates a pneumatic motor mounted on the end extension of the bottom wall or board 14. Said motor drives a crank shaft 42 which carries a sprocket wheel 43 at one end (see Fig. 1); 44 indicates a horizontal drive shaft arranged intermediate the shaft parts 17 and 21. This shaft 44 has bearing between its ends in the standard 18, and at its ends in upright standards 45 and 46 respectively, the one (45) being fixed to the outer surface of the box wall 12 and the other (46) being fixed to and rising from the extension of the bottom wall 14, as shown in

Fig. 1. Fixed to the outer end of the shaft 44 near the standard 46 is a sprocket 47 which is driven by a chain 47^a from the sprocket 43 on the crank shaft 42. Feathered on the inner end of the shaft 44 adjacent to the standard 45 is an elongated spur pinion 48 which meshes with a spur gear 49 on the winding spool shaft part 21. Loose on the shaft 44 near the bar 18 is a sprocket wheel which through a chain 51 drives a sprocket 52 on the music roll shaft part 17.

55 53 indicates a combined clutch shifting and braking bar which is pivoted at a point intermediate its ends on a bracket 54 extending laterally from the side wall 12. Said lever carries a pin 55 which extends into a peripheral groove in one end of the pinion 48, and said pinion has a longitudinal pin 56 which, when the pinion is shifted endwise in one direction extends into the path of a similar pin 57 on the sprocket 50 so as to be driven thereby. The bottom end of the lever is connected in any convenient manner with the actuating member in the control board of the piano, while the top end of said lever coacts with the brake shoe 58 associated with a disc 59 on the shaft part 17. When the lever 53 is in the position shown in Fig. 1, the pinion 48 will drive the gear 49 to wind the perforated sheet upon the spool 19 and when said lever is in its other position, the sprocket 50 is clutched or connected to the pinion 48 through the pins 56—57 to drive the shaft part 17 to rewind the perforated sheet upon the spool 15^a.

59 58 indicates a relatively short horizontal shaft, arranged a short distance below the winding spool shaft part 21. The right hand end 59 is screw-threaded and extends through a threaded hole in the standard 46, said thread being quite fine, preferably about sixty-four threads to the inch. The left hand end of said shaft bears in an aperture in the standard or bar 18 and to said end is fixed a peripherally grooved collar 60. (See Figure 5.) The vertical leg 61 of an angular bar 62 is operatively engaged with the grooved collar 60 while the horizontal leg 63 of said bar is secured to the adjacent end of the bottom flange 25 of the tracker bar 22.

65 Fixed to the threaded end 59 of the shaft 58 adjacent the standard 46 is a comparatively large metallic disc 64, the periphery of which is provided with fine gear teeth 65. To one face of said disc is secured a fibre disc (see Fig. 7) to deaden the "ring" or resonance in said disc when engaged by another toothed member as will later appear. Fixed to the shaft 58, between the standard 18 and the disc 64, is a spur gear 67. This gear meshes with a small spur gear 68 loose on a stud 69 (see Fig. 6) which is fixed in an arm 70. The bottom end of said arm engages the grooved hub 71 of the

gear 67 and the top end of said arm is forked as at 72 (see Fig. 6) to embrace opposite sides of the shaft 44. The arrangement of the arm 70 is such that it cannot 5 move endwise with respect to the associated shafts 44—58 nor can there be a rotative movement of said arm; consequently the two gears 67 and 68 are always maintained in their proper relation. Fixed to the face of 10 the gear 68 adjacent the disc 64, is a substantially small disc 73 having its periphery provided with fine gear teeth.

75 indicates a peripherally grooved collar, endwise movable on the shaft 44 between the vertical planes of the discs 64 and 73. Said disc carries a longitudinal pin 76 at its right hand end which extends through a hole 77 in the web of the sprocket wheel 47. By this construction it is apparent that 15 the collar 75 may be shifted endwise on the shaft 44 between predetermined limits and still be driven rotatively by the sprocket 47. The right hand end of the collar is provided with fine teeth 78 adapted to mesh 20 with the teeth 65 of the disc 64 when the collar is moved in one direction, while the left hand end of the collar is reduced in diameter and is provided with fine teeth 25 79 (see Figs. 1 and 7) adapted to mesh with the teeth of the disc 73 when the collar is moved endwise of the shaft in the other direction. The teeth 78 and 79 are cut in parts of the collar 75 which are diametrically smaller than the collar and its hub 30 part, so that shoulders are provided which engage the marginal faces of the discs 64 and 73 and limit the endwise movement of the collar 75 in both directions. The collar 35 75 is provided between its ends with a peripheral groove 80 to receive the forked end 81 of an arm 82 (see Figs. 7 and 8), the other end of which is fixed to the extreme right hand end 34^a of the rod 34 before 40 mentioned.

45 The operation of the tracking mechanism is as follows:—When a roll is being played, the marginal edges of the sheet 15 pass over the guide plates 35 and over the tracker bar 22 on the way to the winding spool 19. Should the sheet shift or weave laterally toward the right so that the perforations in the music sheet move out of 45 register with the openings on the tracker bar, an endwise movement in the same direction is imparted to the shift rod 34 and collar 75. This will move the teeth 78 on 50 said collar into mesh with the teeth 65 of the disc 64 and rotate said disc and the shaft 58 to which it is fixed, in one direction. By reason of the screw threaded bearing which the end 59 of said shaft 58 has in the standard 46, an endwise movement is imparted to the shaft 58. Said 55 movement of the shaft will, through the collar 60 and angle bar 62, shift or pull 60 the tracker bar 22 to the right to bring the openings in the same to again register with the perforations in the music sheet. As said shaft 58 moves endwise toward the right under the screw thread action before-mentioned, the disc 64 will move away from and out of mesh with collar 75, the parts all remaining in this last position as long as the perforations in the note sheet and the openings in the tracker bar 22 register. 75

75 indicates a peripherally grooved collar, endwise movable on the shaft 44 between the vertical planes of the discs 64 and 73. Said disc carries a longitudinal pin 76 at its right hand end which extends through a hole 77 in the web of the sprocket wheel 47. By this construction it is apparent that 15 the collar 75 may be shifted endwise on the shaft 44 between predetermined limits and still be driven rotatively by the sprocket 47. The right hand end of the collar is provided with fine teeth 78 adapted to mesh 20 with the teeth 65 of the disc 64 when the collar is moved in one direction, while the left hand end of the collar is reduced in diameter and is provided with fine teeth 25 79 (see Figs. 1 and 7) adapted to mesh with the teeth of the disc 73 when the collar is moved endwise of the shaft in the other direction. The teeth 78 and 79 are cut in parts of the collar 75 which are diametrically smaller than the collar and its hub 30 part, so that shoulders are provided which engage the marginal faces of the discs 64 and 73 and limit the endwise movement of the collar 75 in both directions. The collar 35 75 is provided between its ends with a peripheral groove 80 to receive the forked end 81 of an arm 82 (see Figs. 7 and 8), the other end of which is fixed to the extreme right hand end 34^a of the rod 34 before 40 mentioned.

45 The operation of the tracking mechanism is as follows:—When a roll is being played, the marginal edges of the sheet 15 pass over the guide plates 35 and over the tracker bar 22 on the way to the winding spool 19. Should the sheet shift or weave laterally toward the right so that the perforations in the music sheet move out of 45 register with the openings on the tracker bar, an endwise movement in the same direction is imparted to the shift rod 34 and collar 75. This will move the teeth 78 on 50 said collar into mesh with the teeth 65 of the disc 64 and rotate said disc and the shaft 58 to which it is fixed, in one direction. By reason of the screw threaded bearing which the end 59 of said shaft 58 has in the standard 46, an endwise movement is imparted to the shaft 58. Said 55 movement of the shaft will, through the collar 60 and angle bar 62, shift or pull 60 the tracker bar 22 to the right to bring the openings in the same to again register with the perforations in the music sheet. As said shaft 58 moves endwise toward the right under the screw thread action before-mentioned, the disc 64 will move away from and out of mesh with collar 75, the parts all remaining in this last position as long as the perforations in the note sheet and the openings in the tracker bar 22 register. 75

It is to be noted that, upon the engagement of the teeth 78 with the teeth 65 of the disc 64, a "ring" or resonance might occur by reason of the diametric size of the disc, but, because of the fibre disc 66 on 80 said metal disc, this "ring" or resonance is eliminated.

Should the perforated music sheet now shift or move laterally toward the left, the collar 75 is caused to move endwise toward the left by means of the shift rod 34 until the teeth 79 on the reduced end part of the collar 75 meshes with the teeth of the disc 73 which through the gears 68 and 67 will 85 rotate the shaft 58 in a direction the reverse of that just described. This reverse rotation of the shaft, with its threaded end 59, will cause said shaft to move endwise toward the left, a like movement being imparted to the tracker bar through the angle bar 62, to bring the openings in the tracker bar again into register with the perforations in the music sheet. By reason of the endwise movement of the shaft 58, the arm 70 90 moves in the same direction withdrawing the disc 73 from mesh with the teeth in the reduced end of the collar 75. Thus no matter in what direction the music sheet shifts or weaves, the tracker bar is shifted endwise to follow the weave of the music sheet, so that complete registry is maintained at all times. 95

With the fine teeth used in the various discs, no noise is produced when the discs are moved into mesh. While I have described the said discs as provided with teeth, other suitable engaging peripheral parts or formations may be employed, permitting operative driving connection between them. 100

The improved registry mechanism is extremely positive and quick in its action and is quite sensitive in operation so as to accommodate any minute weaving of the music sheet. The device is noiseless and does not include such small parts as will wear rapidly and thus develop a loose play which must be taken up by fine adjustments. 115

The stops 34^b on the shift rod 34 prevents accidental or careless displacement of the rod, by hand or otherwise, beyond the limits of the endwise movement which it is intended to have. 120

After a music sheet has been once played 125

and it is rewound upon its roll, it has been found by actual operation that, upon a replaying of the music sheet, no weaving occurs in the same.

5 While in describing my invention I have referred to certain details of mechanical construction and arrangement of parts, I do not wish to be limited thereto except as is pointed out in the appended claims.

10 I claim as my invention:—

1. A tracker mechanism for automatically operated musical instruments comprising in combination, an endwise movable tracker bar, a control member movable with the lateral movement of the music sheet, a rotative endwise movable shaft connected to the tracker bar, said shaft having a threaded bearing to impart limited endwise movement in either direction to said shaft, spaced 15 driven members fixed to said shaft, and a rotative driving member intermediate said driven members, adapted for engagement with either as the control member is shifted.

2. In combination with a music sheet roll 20 supporting shaft and an endwise movable tracker bar over which the music sheet is drawn, a drive shaft for the music sheet roll, normally inactive means operatively connected to the tracker bar for imparting an

30 endwise movement thereto, an endwise movable rod operatively engaged with the music sheet, and a device on the drive shaft actuated by said rod in the weaving of the music sheet for directly connecting said normally inactive means to the drive shaft for shifting the tracker bar.

3. In combination with a music sheet roll 40 supporting shaft and an endwise movable tracker bar over which the music sheet is drawn, a drive shaft for the music sheet roll, an endwise movable shaft adjacent the drive shaft, operatively connected to the tracker bar, and means on the drive shaft actuated in the weaving of the music sheet for connecting the drive shaft directly to said second shaft and imparting an endwise movement thereto.

4. In a mechanism of the kind described, 50 the combination of a music sheet roll element, and a tracker bar element, the one element being endwise movable with respect to the other, a shaft mounted for endwise movement when rotated, a drive shaft for the music sheet roll element, and means on the drive shaft operable in the weaving of the music sheet for directly rotating said endwise movable shaft to produce an endwise relative movement between said elements.

5. In a mechanism of the kind described, 60 the combination of a music sheet roll element, and a tracker bar element, the one element being endwise movable with respect to the other, a shaft mounted for endwise movement when rotated, a member opera-

tively connecting said shaft with a tracker bar, and means operable in the weaving of the sheet for rotating said shaft, the endwise movement of which is transmitted through the said connecting member to the tracker 70 bar.

6. In a mechanism of the kind described, 75 the combination of a music sheet roll and a tracker bar adapted for endwise movement, a shaft, means for supporting said shaft, one end of said shaft having a threaded engagement in said supporting means, so that when said shaft is rotated an endwise movement is imparted thereto, a device connecting the shaft and tracker bar, and means operable 80 in the weaving of said music sheet for rotating said shaft.

7. In a mechanism of the kind described, 85 the combination of a music sheet roll element, and a tracker bar element, the one element being endwise movable with respect to the other, a drive shaft for the music sheet roll element, a second shaft mounted for endwise movement when rotated, a bar connecting said second shaft with one of 90 said elements, and means on the drive shaft operable in the weaving of the music sheet for directly connecting said second shaft to the drive shaft.

8. In a mechanism of the kind described, 95 the combination of a music sheet roll and an endwise movable tracker bar, a drive shaft for said roll, a second shaft mounted for endwise movement when rotated, a device connecting said second shaft with the tracker bar, a rod, endwise movable in the weaving of the music sheet, and coacting means on said shafts adapted to be operatively connected by said rod, for rotating said second shaft directly from the drive shaft.

9. In a mechanism of the kind described, 100 the combination of a music sheet roll and an endwise movable tracker bar, a drive shaft for said roll, a second shaft mounted for endwise movement when rotated, a device connecting said second shaft with the tracker bar, a rod, endwise movable in the weaving of the music sheet, gearing on said second shaft for rotating the same in either direction, a collar slidable on the drive shaft into and out of engagement with said gearing, and means connecting the collar with said rod.

10. In a mechanism of the kind described, 110 the combination of a music sheet roll and an endwise movable tracker bar, a drive shaft for said roll, a second shaft mounted for endwise movement when rotated, a device connecting said second shaft with the tracker bar, a rod, endwise movable in the weaving of the music sheet, two sets of spced gears fixed to said second shaft, a gear collar on the drive shaft, intermediate said sets of gears, and an arm connecting said rod with said collar whereby said collar 115

is shifted in the endwise movement of the rod into and out of engagement with either gear set.

11. In a mechanism of the kind described, 5 the combination of spaced, upright standards, a drive shaft journalled therein, a second shaft, one end of said second shaft being journalled in one of said standards and the other end of said shaft being threaded 10 through the other standard, spaced gears on said second shaft, and a gear collar slidable on and rotative with the drive shaft in a plane between said gears and adapted to be moved into engagement with either, whereby 15 said second shaft receives a simultaneous rotative and endwise movement.

12. In a mechanism of the kind described, the combination of spaced, upright standards, a drive shaft journalled therein, a second shaft, one end of said second shaft being journalled in one of said standards and the other end of said shaft being threaded 20 through the other standard, a large gear fixed to said second shaft near one of said standards, a second gear having a hub fixed to said second shaft near the other standard, an upright plate carried by the gear hub and engaging the drive shaft, a third gear journalled on the plate and meshing with 25 the second gear, and a gear collar on the drive shaft adapted to be moved endwise of the drive shaft into operative engagement with the large gear or said third gear.

13. In a mechanism of the kind described, 30 the combination of spaced, upright standards, a drive shaft journalled therein, a second shaft, one end of said second shaft being journalled in one of said standards and the other end of said shaft being threaded 35 through the other standard, a large gear fixed to said second shaft near one of said standards, a second gear having a hub fixed to said second shaft near the other standard, an upright plate carried by the gear hub 40 and engaging the drive shaft, a third gear journalled on the plate and meshing with the second gear, and a gear collar on the drive shaft adapted to be moved endwise of the drive shaft into operative engagement 45 with the large gear or said third gear, said gear collar including peripheral shoulders which prevent its being shifted beyond engagement with said large and said third gears. 50

14. In a mechanism of the kind described, 55 the combination of a music sheet roll element and a tracker element, the one being endwise movable with respect to the other, means actuated in the weaving of the music sheet for imparting an endwise movement to one of 60 said elements, a rod operatively engaged with said last mentioned means, and guide plates carried by said rod and engaged with the margins of the music sheet, said guide plates having end flanges defining channels 65 to receive the edges of said music sheet, said flanges overhanging said edges so that said edges cannot become displaced therefrom.

15. In a mechanism of the kind described, 70 the combination of an endwise movable rod, guide plates on said rod over which the margins of the music sheet must pass, said guide plates being pivoted on said rods to swing within certain limits, and spring-pressed means between said rods and plates 75 urging said plates toward the music sheet.

16. In a mechanism of the kind described, the combination of a music sheet roll element and a tracker element, the one being endwise movable with respect to the other, 80 means actuated in the weaving of the music sheet for imparting an endwise movement to one of said elements, a rod operatively engaged with said last mentioned means, guide plates carried by said rod for engaging the 85 margins of the music sheet so that said rod is moved endwise under the weaving action of the music sheet, and means on said rod for limiting the endwise movement thereof. 90

17. In combination with a tracker box 95 having side walls, bracket plates fixed to the said side walls, said bracket plates each including a front flange adapted to be screwed to the front edges of said side walls, and a side flange adapted to engage the inner surface of said side walls, said side flanges having openings therein to receive the ends of a tracker bar, and in which said tracker bar has bearing for an endwise movement.

In testimony that I claim the foregoing as 100 my invention, I affix my signature in the presence of two witnesses, this 11th day of May, 1922.

THEODORE M. REIMERS.
